DENNIS M. WELCH AND CLARE WARNER, OF LANSING, MICHIGAN

CAN COVER

Application filed May 17, 1929. Serial No. 363,820.

The object of this, our present invention, is the provision of simple means for automatically and positively locking a cover on a garbage or like can, the construction being such that the cover may be readily removed by an outward pull upon an element arranged below the handle of the pan.

A further object is the provision of a locking means of this type which can be attached to covers of any ordinary garbage or like can constructions.

To the attainment of the foregoing and other objects which will present themselves as the nature of the invention is better understood, the improvement also consists in certain other novel features of construction, combination and operative association of parts, one satisfactory embodiment of which is disclosed by the accompanying drawings.

20 In the drawings:

Figure 1 is an approximately central longitudinal sectional view through the upper portion of a garbage or like can and the cover therefor, showing the latter locked to 25 the can in accordance with this invention.

Figure 2 is a sectional view approximately on the line 2—2 of Figure 1.

Figure 3 is a bottom plan view of the cover to illustrate the protective housing in 30 which the locking mechanism is arranged.

Figure 4 is a perspective view of one of the arms employed.

In the drawings the numeral 1 designates the upper portion of a garbage or like can 35 that is provided at its mouth with the usual outstanding bead 2.

The cover 3 for the can is of the usual construction and is designed to have its depending flange arranged loosely around the 40 mouth of the can 1. The cover is provided on its top with the usual handle 4.

In carrying out our invention we secure to the under face of the cover 3 at plate 5 that has its ends formed with depending 45 right angular portions 6. To this plate, at the opposite sides of the center thereof and consequently at the opposite sides of the center of the cover we secure spaced depending plates 7. Between each pair of plates we 50 pivot, as at 8, the bent portions of angle

arms 9. The inner ends of these arms are formed with elongated slots 10 that are received in the bifurcated ends of a block 11 which is fixed on the lower end of a post or bolt 12. Pivot pins 13 pass through the 55 bifurcated ends of the block and through the slots 10. The bolt or post 12 passes through a central opening in the plate 5 and through the top of the cover 3 and has fixed on its outer end a hand grip 14 which is disposed within the handle 4, but is spaced therefrom. A spring 15 surrounds the post or bolt 12 and exerts a tension between the plate 5 and the block 11, causing the angle arms 9 to swing to the position illustrated 60 by Figure 1 of the drawings.

The upper ends of the angle arms have loosely connected thereto rods 16 which are guided through openings 17 in the depending portions 6 of the plate 5. The outer 70 ends of the rods 16 are bent to provide rounded and jaw portions 17 which are received through slots 18 in the sides of the flanged cover 3. These rounded or hooked portions 17 are adapted to engage with the beads 2 of the can 1. The rounded or jaw portions merge into outwardly extending ends 19 which are also received through the openings 18 and these angle portions are 75 designed to ride over the beads 2 80 when the cover is inserted on the can with tension of the spring 15 to permit of the said cover being arranged on the can without necessitating the operator engaging with 85 the grip 14. To remove the cover, however, the operator grasps both the handle 4 and the grip 14 and exerts a pull upon the latter which, of course, will draw the bolt or post outwardly through the cover and swing the angle arms to cause the rods 16 to be moved outwardly through the openings 18 and thereby bring the rounded portions or jaws 17 of the said rods out of engagement 90 with the bead 2. To limit such outward movement of the rods the flange of the cover is preferably provided with a strip or plate 20 which bridges the openings 18 at the center thereof and which plates will contact 95 with the inwardly rounded portions pro- 100

vided between the jaws 17 and the angle extensions or ends 19 of the said jaws.

6 To protect the mechanism above described we secure on the inner face of the cover a substantially cross sectionally U-shaped housing 21 as best disclosed by Figures 2 and 3 of the drawings.

10 The construction and advantages of our improvement will, it is thought, be understood and appreciated so that further detailed description will not be required.

Having described the invention, we claim:

15 A garbage or like can having its mouth formed with an outwardly extending continuous bead and a flanged cover for said can, and said cover having a handle thereon, a post movable through the top of the cover, a grip on the outer end of the post arranged within the handle of the cover, a 20 block secured to the lower end of the post and having bifurcated ends, a spring surrounding the post and exerting a pressure between the cover and the block, depending elements supported from the cover and arranged to the opposite sides of the block, 25 angle arms pivoted at their bends to said elements and having their inner ends provided with elongated slots which are received in the bifurcated ends of the block, 30 pivots passing through the block and said slots, rods secured to the second ends of the angle levers, guides carried by the cover for the rods, said rods having their outer ends rounded upon themselves to provide 35 jaws and from thence extended outwardly at a downward angle, the cover having slots to receive the said ends of the rods therethrough, the jaw ends of the rods designed to engage with the beads of the can, as and 40 for the purpose set forth.

In testimony whereof we affix our signatures.

DENNIS M. WELCH.
CLARE WARNER.
